ARTHUR F. POOLE, OF PELHAM MANOR, NEW YORK, AND FREDERICK A. HART, OF NEW BRITAIN, CONNECTICUT, ASSIGNEES TO REMINGTON ACCOUNTING MACHINE CORPORATION, OF NEW YORK, N. Y., A CORPORATION OF NEW YORK.

CALCULATING MACHINE.

Application filed September 29, 1922. Serial No. 591,296.

To all whom it may concern:

Be it known that we, ARTHUR F. POOLE and FREDERICK A. HART, citizens of the United States, and residents, respectively, of Pelham Manor, in the county of Westchester and State of New York, and New Britain, in the county of Hartford and State of Connecticut, have invented certain new and useful Improvements in Calculating Machines, of which the following is a specification.

Our invention relates to computing machines and the object thereof, generally stated, is to provide an improved roller or wheel construction for guiding the carriages or trucks of such machines.

Our invention consists in certain features of construction, arrangements of parts and combinations of devices set forth in the following specification and more particularly pointed out in the appended claims.

The invention is shown embodied in the present instance in a Remington accounting machine, only so much of said machine being shown as is necessary to illustrate our invention in its embodiment therein. It should be understood, however, that the invention may be included in other makes of accounting machines.

In the accompanying drawings, wherein like reference characters indicate corresponding parts in the different views,

Figure 1 is an enlarged detail vertical fore-and-aft central sectional view of a portion of the Remington accounting machine embodying our invention, the upper roller and its support being shown in side elevation.

Figure 2 is a much enlarged detail vertical fore-and-aft sectional view of the upper roller and the means for supporting and adjusting the same, together with a portion of the truck with which the roller coacts; the section being taken on the line 2—2 of Fig. 3 and looking in the direction of the arrows at said line.

Figure 3 is an enlarged detail top plan view of the upper roller and its supporting means.

The Remington accounting machine comprises a typewriting machine, to the top plate *a* of which brackets *b* are secured by screws *c*. Screws *d* fixedly connect the framework *1* of the actuator of the com-

puting mechanism to the brackets *b*. Arms *55* or brackets *2* project forwardly from the ends of the typewriter carriage, and at their forward ends are loosely connected to bars or brackets *3*; one fastened by screw bolts and nuts *e* to each end of the computer *4* on which may be mounted one or more totalizers *5*. Each of said totalizers contains computing mechanism including a series of gear wheels *6* which are adapted to mesh one at a time with the master wheel *7*; the latter constituting part of the actuating mechanism driven by the numeral keys of the typewriting machine. As the typewriter carriage moves towards the left in the process of writing and computing a *70* number, the wheels *6* in the computing zone move one after another into mesh with the master wheel *7*. Said gears *6*, and totalizers in which they are supported, must of necessity be guided across the master wheel *75* with a considerable degree of precision as otherwise the teeth of said wheels might collide, and if the wheels *6* and *7* do not mesh properly the operation may be hard or otherwise imperfect. In the Remington accounting machine the truck *4* is somewhat loosely connected with the arms *2* fixed to the typewriter carriage, as pointed out, for example, in the patent to George A. Seib, No. 1,423,741 dated July 25, 1922. *85* This is in order to enable the truck *4* to have a small limited amount of free movement at its ends with respect to the bracket arms *2*. The accurate guiding of the truck *4* is effected at the middle of the machine *90* substantially in the fore-and-aft vertical plane of the master wheel, this being the point at which accuracy is required. To this end the truck has been given a cross section like that indicated in Fig. 1, so as to provide three tracks or guideways *8*, *9* and *10*. The trackway *8* is at the bottom of the truck and faces downward and is supported by a roll or wheel *11* which carries the vertical weight of the truck and the *100* totalizers mounted on it. The track *9* is at the bottom of the truck and faces rearward and presses against a roll or wheel *12*. The vertically disposed bearing face of the trackway *10* is at the top of the truck and presses forward against a roller which resists the forward thrust of the truck. The usual upper roller situated at

this point is replaced by the special roller 13 of our invention constructed and mounted in a manner which will hereinafter appear. The roller 11 is mounted in the usual manner on a spindle 14 arranged in an eccentrically disposed bearing in the sleeve or bushing 15, to provide for an up and down adjustment of the roller 11 by a turning adjustment of the bushing, as pointed out in the patent to Oscar Woodward, No. 1,401,225 dated December 27, 1921. The roller 12 is mounted on an eccentrically arranged bearing 16 on a pin 17, so that a turning adjustment of said pin will effect a fore-and-aft adjustment of the roller 12, as pointed out in said last mentioned patent.

Heretofore the upper roller that coated with the track 10 was horizontally disposed; turning on a vertical axis, and was necessarily limited in size by the space in which it was received between the face of track 10 and the overlapping portions of the totalizers carried by the truck. The truck ordinarily runs with the greater part of its weight supported on the three rollers 11, 12 and 13 and it will be seen that the center of gravity of the truck is forward of the roller 11. When a number of totalizers are mounted on and project forward from the truck there is a constant forward pressure or thrust exerted against the upper roller 13. In some instances this overhanging weight becomes considerable, and it has been found that by reason of the small diameter of the upper front roller it failed to turn when coating with the track 10. The track 10 sliding against the roller gradually caused wear thereon; sometimes sufficient to wear a flat face on the roller. Then it would be necessary to replace the worn roller with a new one. Wear on the upper roller allows the upper part of the truck to drop forward and destroy the nice adjustment and relation between the wheels 6 and the master wheel 7.

The main object of our invention is to overcome these disadvantages and to provide simple and highly efficient means which may readily replace those formerly employed to guide the upper portion of the truck, without modifying other structural features of the machine. To these ends we provide a bearing block 18 apertured at 19 to receive two screws 20 by which the block is secured at the center of the machine in the plane of the master wheel 7 and on the top of the fixed frame 1 of the actuator. The block is split at 21 to form two jaws and in the body of the block and between these jaws is formed a smooth bore bearing 22, the axis of which is inclined. A cylindrical spindle or support 23 is received and fits in this bearing and constitutes a support for the roller 13. A headed screw 24 is threaded at one

end only and passes through aligned openings that extend transversely through the jaws of the block, as shown in Fig. 3. The transverse opening in which the threaded end of the screw is received is tapped to 70 coat with the threads on the screw, whereas the unthreaded portion of the shank of the screw passes freely through the opening in the other jaw. By loosening the screw 24 the jaws of the bearing may spring apart 75 sufficiently to free the spindle from the clamping pressure by which it is held; enabling the spindle to be adjusted either axially or around its axis; and by tightening said screw, said spindle may be held securely in 80 adjusted position. A nick 25 may be made in the upper end of the spindle to facilitate its turning adjustment with the aid of a screw driver.

The wheel 13 is eccentrically journaled on 85 the forward end of the spindle 23 by a suitable ball bearing which, in the form shown in the present instance is constructed as follows: Arranged eccentrically in the spindle 23 and longitudinally thereof is a 90 tapped opening 26. This opening receives a screw 27 which is formed at its lower end with a head 28 forming one section of a two-part ball-bearing member. This head has a trackway 29 on which anti-friction balls 30 95 roll and a nick 31 to receive a screw driver and enable the screw to be threaded into the opening 26. A second section 32 of the bearing member has a trackway 33 on which the balls 30 roll. This section is apertured 100 centrally for the passage therethrough of the shank of the screw 27. A washer-like spacing member or convolute 34 of a soft steel wire coil surrounds the shank of the screw and is interposed between the two 105 sections 28 and 32, determining the extent of relative adjustment between the sections towards each other after the requisite compression of the spacing member between 110 said sections has been once effected. The back or upper side of the section 32 bears against the lower end of the spindle 23 when the screw with the bearing member thereon is threaded home as shown in Fig. 2, thus holding the bearing sections firmly 115 together and against displacement from the spindle or support 23. The inclined circular series of balls 30 are received in a raceway 35 in the roller 13 that is V-shaped 120 in cross section, so that the said roller is supported with its plane inclined.

It will be seen that this roller has two beveled contact bearing faces 36 and 37, each inclined to the plane of the roller and to the axis thereof. We prefer to slightly curve the contact faces in cross section so that each presents only a point bearing on the flat bearing face of the track with which it coacts. The contact face 36 normally 125 coacts with the vertically disposed bearing 130

face of the track 10, the roller resisting the forward thrust of the truck at the upper portion thereof. The bearing face 37 of the roller is normally out of contact with a horizontally disposed bearing face of track 38 on the truck, but is adapted to coat therewith to limit the upward movement or thrust of the truck, that formerly was limited by a set screw carried by the frame 1. It will be understood therefore that the roller 13 not only resists the forward thrust of the truck but also limits its upward thrust, and that in thus attaining these ends the roller 13 coats with two bearing faces on the double track 10-38 arranged at right angles to each other and at angles to the axis of the roller 13. This roller is purposefully arranged to permit a slight upward play of the truck and also to permit a slight rearward play at its upper portion, which rearward play is limited by the usual stop screw 39, whereas a slight forward play at the lower portion of the truck is limited in the usual manner by a vertically disposed track-face 40 on the truck coacting with the rear side of the roller 11.

In order that the roller 13 may be properly adjusted both up and down with reference to the track 38 and fore-and-aft of the machine to determine its position to resist the forward thrust of the track 10, it is merely necessary to adjust the spindle or support 23. Said spindle has two adjustments, viz, by sliding it endwise and by turning it. The first adjusts the wheel 13 in the direction of its axis, and the second, by reason of the eccentric mounting of said wheel, adjusts the latter transverse to its axis. By a combination of the two the wheel can be brought to correct position both front and back and also up and down. The means for effecting these adjustments in two directions at substantial right angles to each other are at all times readily accessible and may be quickly effected and once attained may be permanently maintained by tightening the screw 24.

It will be understood that by supporting the roller 13 in an inclined position as shown, said roller may extend above or overlie the totalizers and is maintained out of the path thereof, and also extends to a position below the upper portion of the totalizers and in the rear thereof where it overlies the truck. It will be seen that this relative arrangement of the parts enables us to employ a roller 13 which has a diameter greater than the thickness of the truck and to provide a bearing face of larger circumference than that heretofore employed. This distributes the wear over a greater circumferential surface on the roller, and such surface being at a greater distance from the axis of the roller than heretofore enables the roller to be more

easily turned in its cooperation with the truck, and also enables us to employ an effective ball bearing and staunch support for the roller by reason of the increased space afforded by the relative arrangement of the parts. 70

In the present instance we secure a pointer 41 which coats in the usual manner with the letter space indices on the part 42 of each totalizer in the median fore-and-aft plane of the machine by the same screws 24 by which the roller supporting block is secured to the frame 1. 75

From what has been said it will be understood that the master wheel 7, and the points of contact of all of the rollers 11, 12 and 13 with their tracks are substantially in the same fore-and-aft vertical median plane of the machine, and that said rollers effectively guide the truck at this point and insure a proper successive engagement between the totalizer wheels 6 and the master wheel 7 as the truck carries the totalizers past said master wheel. 80

A combination including a "truck, and means for effecting an adjustment of said truck transversely to the line of its travel comprising a roller, a ball bearing for said roller, and a rotatively adjustable member on which said ball bearing is mounted eccentrically of said rotatively adjustable member," is the sole invention of Frederick A. Hart and is claimed by him in a companion application, Serial No. 604,182 filed December 1, 1922. 85

What we claim as new and desire to secure by Letters Patent, is:—

1. In a calculating machine, the combination with a calculator truck, and means for guiding said truck comprising a guide track on the truck, and a roller that coats with said track to resist a forward thrust of the truck and also to limit an upward thrust thereof, the roller being fixed against traveling movement but free to rotate on its own axis. 105

2. In a calculating machine, the combination with a calculator truck, and means for guiding said truck comprising a guide track on the truck, and an inclined roller that coats with said track to resist a forward thrust of the truck and also to limit an upward thrust thereof, the roller being fixed against traveling movement but free to rotate on its own axis which is inclined. 110

3. In a calculating machine, the combination with a calculator truck, and means for guiding said truck comprising a guide track on the truck, and a roller that coats with said track to resist a forward thrust of the truck and also to limit an upward thrust thereof, the roller being fixed against traveling movement but free to rotate on its own axis and having a bearing surface inclined to its axis. 115

4. In a calculating machine, the combination with a calculator truck, and means for guiding said truck comprising a guide track on the truck, and a roller that coacts with said track to resist and limit transverse movements of the truck in certain directions and not in others, said roller being fixed against traveling movement but free to rotate on its own axis and having a beveled bearing surface which coacts with said rail. 5. In a calculating machine, the combination with a calculator truck, and means for guiding said truck comprising a guide track on the truck, and a roller that coacts with said track to resist or limit the thrust of the truck in two directions at substantially right angles to each other, the roller being fixed against traveling movement but free to rotate on its own axis and having oppositely beveled bearing faces which coact with bearing faces on said track arranged at right angles to each other. 6. In a calculating machine, the combination with a calculator truck, and means for guiding said truck comprising a guide track on the truck, and an inclined roller that coacts with said track to resist a forward thrust of the truck and also to limit an upward thrust of the truck, the roller being fixed against traveling movement but free to rotate on its own axis which is inclined and said roller having oppositely disposed beveled bearing surfaces which coact respectively with an upright bearing face and a horizontal bearing face on said track. 7. In a calculating machine, the combination of a totalizer-carrying truck and guiding means therefor comprising a centrally located supporting roller that receives the down thrust of the truck and a centrally located inclined roller that resists the forward thrust and also limits the upward thrust of the truck. 8. In a calculating machine, the combination of a master wheel, a totalizer-carrying truck, and guiding means for said truck comprising a roller which resists the down thrust of the truck, a second roller which resists the rearward thrust of the truck at its lower portion, and a third inclined roller which resists a forward thrust of the truck and also limits an upward thrust thereof, all of said rollers being included in a fore-and-aft plane which includes the master wheel. 9. In a calculating machine, the combination of a totalizer-carrying truck; guiding means therefor including a centrally located inclined guide roller located above the truck and co-operative therewith to resist a forward thrust of the truck at the top thereof and also to limit an upward thrust of the truck; and means for effecting an axial adjustment of said roller and also for effecting an adjustment of said roller transversely of its axis. 10. In a calculating machine, the combination of a totalizer-carrying truck, and guiding means therefor comprising a split supporting block having a bearing therein, a screw to adjust the jaws of the split block and thereby loosen or tighten the walls of the bearing, a cylindrical support contained in and adjustable both axially and rotatably in said bearing and held in its adjusted position by tightening the jaws of the split block, a ball bearing mounted eccentrically on said cylindrical support, a guide roller, anti-friction balls between said guide roller and ball bearing, and a track on said truck with which said guide roller coacts. 11. In a calculating machine, the combination of a totalizer-carrying truck, and guiding means therefor comprising a split supporting block fixed on the frame of the machine and having an inclined bearing therein, a screw to adjust the jaws of the split block and thereby loosen or tighten the walls of the bearing, an inclined cylindrical support contained in and adjustable both axially and rotatably in said bearing and held in its adjusted position by tightening the jaws of the split block, a ball bearing mounted eccentrically on said cylindrical support, an inclined guide roller, anti-friction balls between said guide roller and ball bearing, and a track on said truck with which said inclined guide roller coacts. 12. In a calculating machine, the combination of a totalizer-carrying truck, and guiding means therefor comprising a split supporting block having a bearing therein, a screw to adjust the jaws of the split block and thereby loosen or tighten the walls of the bearing, a cylindrical support contained in and adjustable both axially and rotatably in said bearing and held in its adjusted position by tightening the jaws of the split block, a ball bearing mounted eccentrically on said cylindrical support, a guide roller having oppositely beveled contact faces, anti-friction balls between said guide roller and ball bearing, and a double track on said truck having contact faces at substantially right angles to each other, one coacting with a beveled contact face on the roller to resist a forward thrust of the truck and the other track face coacting with the other beveled contact face on the roller to limit the upward thrust of the truck. 13. In a calculating machine, the combination of a totalizer truck having a track thereon, a totalizer carried by said truck, and a guide roller for said truck arranged in an inclined plane and extending over the truck and above the path of the totalizer and coacting with said track, whereby a roller of greater diameter than the thickness of the truck may be employed. 14. In a calculating machine, the combination of a totalizer truck having a track there-

on, a totalizer carried by said truck, and a guide roller for said truck arranged in an inclined plane and extending over the truck and above the path of the totalizer and co-acting with said track, a ball bearing support for said roller, and means whereby said roller may be adjusted in two directions at substantially right angles to each other, the construction and arrangement of the parts being such that a guide roller of greater diameter than the thickness of the truck may be employed and ample space is provided for the effective support of said roller on ball bearings and for the provision of adjusting means for the roller.

15. In a calculating machine, the combination of a totalizer-carrying truck, and guiding means therefor comprising a supporting spindle mounted for turning and axial adjustment and having an eccentrically arranged tapped opening in one end thereof, ball bearing members including a screw that is received in said tapped opening and provides for a relative adjustment between the bearing members and for holding the members on said supporting spindle, a guide roller, anti-friction balls between said roller and bearing members, and a track on said truck with which said guide roller coacts.

20. 16. In a calculating machine, the combination of a totalizer-carrying truck, and guiding means therefor comprising an inclined supporting spindle mounted for turning and axial adjustment and having an eccentrically arranged tapped opening in one end there-

of, inclined ball bearing members including a screw that is received in said tapped opening and provides for a relative adjustment between the bearing members and for holding the members on said supporting spindle, an inclined guide roller having two contact faces, anti-friction balls between said roller and members and a double track on said truck with which the two contact faces on said guide roller coact.

25. 17. In a calculating machine, the combination of a totalizer truck having a track thereon; a totalizer carried by the truck; and guiding means for said truck including a centrally located lower roller to resist the down thrust of the truck, and a second centrally located upper guide roller arranged in an inclined plane and extending over the truck and above the path of the totalizer and coacting with said track to resist a forward movement of the truck and also to limit an upward thrust thereof, the construction and arrangement of the parts being such that the said upper roller may have a diameter greater than the thickness of the truck and may be effectively supported on the machine.

Signed at the borough of Manhattan, city of New York, in the county of New York, and State of New York, this 27th day of September, A. D. 1922.
